UNITED STATES PATENT OFFICE.

GEORGE E. HOTTENSTEIN AND ROBERT Z. FARMER, OF BISBEE, ARIZONA.

FLUID-OPERATED BRAKE.

1,116,819.

Specification of Letters Patent. Patented Nov. 10, 1914.

Application filed January 28, 1914. Serial No. 815,019.

To all whom it may concern:

Be it known that we, GEORGE E. HOTTENSTEIN and ROBERT Z. FARMER, citizens of the United States, residing at Bisbee, in the county of Cochise and State of Arizona, have invented certain new and useful Improvements in Fluid-Operated Brakes, of which the following is a specification, reference being had to the accompanying drawings.

This invention relates to certain improvements in fluid operated brakes and has relation more particularly to a device of this general character wherein the brake is set or applied upon decrease of pressure in the train line; and an object of the invention is to provide a device of this general character having novel and improved means whereby the brake proper is under control of two fluid-controlled elements, one of such elements being operatively supported by the other but capable of movement independently thereof.

The invention also has for its object to provide a device of this general character having novel and improved means whereby the fluid at either side of the piston is discharged directly to the atmosphere independently of the train line.

Furthermore, the invention has for its object to provide a device of this general character having, in part, novel and improved means whereby the auxiliary reservoir is charged upon the admission of the fluid under pressure within the brake cylinder, the fluid for such auxiliary reservoir passing through the brake cylinder; and having, in part, novel and improved means whereby the degree of pressure within the auxiliary reservoir may be automatically controlled.

The invention consists in the details of construction and in the combination and arrangement of the several parts of our improved fluid operated brake whereby certain important advantages are attained and the device is rendered simpler, less expensive and otherwise more convenient and advantageous for use, all as will be hereinafter more fully set forth.

The novel features of the invention will be carefully defined in the appended claims.

In order that our invention may be the better understood, we will now proceed to describe the same with reference to the accompanying drawings, wherein—

Figure 1 is a diagrammatic view of a

brake mechanism arranged in accordance with an embodiment of our invention; Fig. 2 is a longitudinal sectional view taken through a brake cylinder as herein embodied; Fig. 3 is a sectional view taken substantially on the line 3—3 of Fig. 2; Fig. 4 is a sectional view taken substantially on the line 4—4 of Fig. 2, with the pistons shown in a different position; Fig. 5 is a sectional view taken through the controlling valve herein disclosed; and Fig. 6 is a similar view taken through the pressure regulating valve herein embodied.

As disclosed in the accompanying drawings, 1 denotes the brake cylinder of predetermined capacity in communication through its rear end, as indicated at 2, with the auxiliary reservoir or air tank 3, such reservoir or tank 3 being also in communication with the brake cylinder through a side wall thereof and in predetermined proximity to the rear end 4 thereof through the medium of the line 5. In communication with the brake cylinder 1 is the cross-over 6 leading from the train line, which may be of any desired construction and which is adapted to be under control, in the general way, of a release valve in the engineer's cab.

Suitably mounted within the brake cylinder 1 and adapted for reciprocating movement therein is the main piston 7 having its periphery provided with suitable packing rings 8 whereby a hermetic or air-tight engagement is had with the interior surface of the brake cylinder.

Formed upon the forward face of the piston 7 and concentrically with the axis thereof is the auxiliary cylinder 9 of predetermined capacity and in which is mounted for reciprocating movement the piston 10, the periphery whereof is also provided with a suitable packing ring, as indicated at 11, for a purpose which is believed to be self-evident. The forward head 12 of the auxiliary cylinder 9 is provided with the axial tubular extension 14 in communication with the auxiliary cylinder 9 and projecting through a suitable stuffing box 15 in the forward or front head 16 of the brake cylinder 105 and in communication with the atmosphere, as indicated at 17. The tubular extension 14 is of such a length as to serve as a guide for the piston 7 in its reciprocating movement and also affords a passage-way for the 110 brake rod 18 operatively connected at its inner end to the piston 10 within the auxil-

iary cylinder 9, as indicated at 19'. The opposite extremity of the brake rod 18 is adapted to be operatively connected with the brake rigging, herein omitted as the specific construction of the brake rigging and the connection of the rod 18 therewith forms no part of our present invention. It is to be observed that the transverse diameter of the rod 18 is less than the similar diameter of the bore of the tubular extension 14 so that the requisite communication between the atmosphere and the auxiliary cylinder 9, hereinbefore indicated at 17, may be afforded.

Interposed in the cross-over 6 is a controlling valve herein shown as comprising a cylinder 19 through one end of which, as indicated particularly at 20 in Fig. 5, is adapted to be admitted the fluid under pressure from the train line. When the pressure in the train line is increased to release the brake, the fluid enters within the cylinder 19 and forces rearwardly the piston 21 until the same has passed the port 22 in a side thereof and in communication with the passage-way 23 afforded at one side of the cylinder 19 and extending longitudinally thereof and terminating in the transverse extension 24 disposed through the rear end of the cylinder 19 and in communication with the atmosphere, as is believed to be clearly shown in Fig. 5. The passage-way 23 is also in communication with that portion of the cross-over interposed between the cylinder 19 and the brake cylinder 1 by the branch 35 passage-way 25. The piston 21 is mounted upon the rod 26 disposed axially of the cylinder 19 and adapted to intersect the transverse extension 24 of the passage-way 23 and to close the same when the piston has been forced inwardly sufficiently to place the port 22 in communication with that portion of the cylinder 19 in advance of the piston 21. It will, therefore, be observed that upon the requisite inward movement of the piston 21 the fluid under increased pressure is free to pass within the brake cylinder 1 and to adjust the main piston 7 to the position shown in Fig. 2 wherein the draft rigging will be moved to release position, as is believed to be self-evident. With the main piston 7 in the position as shown in Fig. 2, it will be observed that the line 5 in communication with both the brake cylinder 1 and the auxiliary reservoir or air tank 3 is open whereby the fluid from the train line is free to enter within such auxiliary reservoir or air tank 3.

We have found in practice that it is essential that the degree of pressure within the auxiliary reservoir or air tank be controlled or limited and in order to automatically effect this control, we interpose within the line 5 the pressure regulating valve, indicated in Fig. 1 and particularly illustrated in Fig. 6 and wherein such valve is shown

as comprising a suitable casing 27 having interposed therein the check valve 28 whereby return of such fluid, after passing through the valve opening 29, is effectually prevented. The casing 27 is also provided with the upstanding basket 30 in communication with the bore 31 of the casing 27, as indicated at 32, and preferably at a point directly above the valve opening 29, which opening 32 is adapted to have projected therethrough the valve member 33 normally maintained in elevated or inoperative position by the expansible member 34, herein disclosed as a coil spring encircling the stem 35 of the valve 33 and interposed between the piston 36 mounted for reciprocating movement within the basket 30, and a suitable abutment 37 positioned at the base of such basket. In communication with that portion of the bore 31, interposed between the auxiliary reservoir or air tank 3 and the check valve 28, is the passage-way 38 produced in one side of the basket, such passage-way 38 being in communication with the interior of the basket at a point above the piston 36 through the medium of the port 39.

In the practical operation of our improved apparatus, we have found that the best results can be obtained when the pressure within the auxiliary reservoir or air tank is at seventy pounds. For this reason, we therefore have the expansible member 34 of such tension as to withstand a pressure up to seventy pounds. By this arrangement, it will be seen that as soon as the pressure within the auxiliary reservoir or air tank becomes in excess of seventy pounds, the pressure within the basket 30 above the piston 36 will exceed seventy pounds and as this pressure is in excess of the adjustment of the expansible member 34, the valve 33 will be caused to descend until it seats upon the valve opening 38 whereby it will be readily seen that continued flow from the train line to within the auxiliary reservoir or air tank will be automatically closed. When it is desired to place the brake in application, the pressure within the train line is reduced. Upon the reduction of the pressure in the train line to below seventy pounds, it will be readily perceived that the pressure within the auxiliary reservoir or air tank which is discharged within the brake cylinder rearwardly of the main piston 7 will cause such piston to move inwardly and in order to create an initial movement of the brake rod 18 to take up any possible slack in the draft rigging, we produce in the inner wall of the brake cylinder in close proximity to the rear head thereof, the elongated grooves or recesses 40 of any predetermined number but preferably four, disposed in equidistant relation, which are adapted to afford communication with that portion of the brake cyl-

inder to the rear of the main piston 7 after the same has been initially moved to a pre-determined distance and which we have found best in practice to be substantially one-quarter of an inch. Produced in the periphery of the main piston 7 is the annular channel or recess 41 whereby requisite communication may be had with the elongated recesses or channels 40 and depending 5 inwardly or radially of such piston 7 is the passage-way 42, herein disclosed as disposed in an angular line, so that the flow of the fluid therethrough may be controlled in a manner as will hereinafter be more particularly referred to. The inner extremity of the passage-way 42 is in communication with the auxiliary cylinder 9 at the rear of the piston 10 whereby upon this slight initial movement forwardly of the piston 7 the 10 fluid from the auxiliary reservoir or air tank 3 will be caused to discharge within such auxiliary cylinder 9 and force the same forward until any possible slack in the draft rigging will be compensated for whereupon 15 the pressure within the auxiliary reservoir or tank will cause the main piston 7 to be moved forward until the brakes are properly applied or set. In order to hold the pressure within the auxiliary cylinder rear- 20 wardly of the piston 10, we interpose within the passage-way 42 a suitable check valve 43, as is particularly shown in Fig. 2. At the time the pressure in the train line is reduced, the piston 21, comprised in the con- 25 trolling valve, is caused to return to the position shown in Fig. 5 by the flow of the fluid within the brake reservoir 1 in advance of the main piston 7 through the passage-way 23 and its angular extension 24 and 30 through the groove or channel 44 produced in the periphery of the stem or rod 26 of the cylinder 21, such groove or channel 44 being of such a length as to assure the requisite communication between the extension 24 and the interior of the cylinder 19 when the 35 piston 21 has been moved forwardly sufficiently to close the extension 24. With the return of the piston 21 to the position as illustrated in Fig. 5, it will be perceived that 40 the transverse opening 45 produced in the outer or free extremity of the rod or stem 26 will be caused to register with the extension 24 whereby the pressure within the brake cylinder 1 in advance of the main pis- 45 ton 7 will be discharged directly to the atmosphere. We also find it of advantage, in order that the pressure within the cylinder 19 may be reduced in order to in no wise interfere or obstruct the operation of the 50 piston 21 upon the increase of pressure in the train line, to provide the port 46 adapted to be in communication with the interior of the cylinder 19 and the opening 45, herein- 55 before referred to, when the parts are in the 60 position as illustrated in Fig. 5. We also 65

find it of advantage, in order to prevent return flow of the fluid, to interpose in the passage-way 23 between the branch passage-way 25 and the induction end of the cylinder 19, a check valve 47 of any conventional type. The flow of the fluid from the auxiliary reservoir or air tank 3 through the passage-way 42 is under control of the valve member 48, herein disclosed as comprised in the piston rod 49, on which are mounted the 70 space pistons 50 and 51 mounted for reciprocating movement within the supplemental cylinder 52 suitably affixed to the side of the auxiliary cylinder 9 and having its outer end, as indicated at 53, open, while the inner 75 end is closed by the adjacent face of the main piston 7.

As is believed to be self-evident, the valve 48 is adjusted into closed position relative to the passage-way 42 by the action of the 80 pressure upon the outer piston 52 which results in such compression of the air between the piston 50 and the closed end of the cylinder 52 as will cause the pistons 50 and 51 to move outwardly, as indicated in 85 Fig. 4, when the pressure within the brake cylinder 1 in advance of the piston 7 is released, the movement of such pistons 50 and 51 being such as to open the passage-way 90 42. It is obvious that when the pressure 95 within the brake cylinder 1 in advance of the piston 7 is increased to release the brakes, means must be provided to reduce the pressure within the auxiliary cylinder 9 to the rear of the piston 7 and, as herein disclosed, we accomplish this through the medium of the passage-ways 54 and 55, the 100 passage-way 54 being in communication with the rear end of the cylinder 9 while the passage-way 55 is in communication with the forward end of the cylinder, while both of such passage-ways are in communication with the supplemental cylinder 52 at a point intermediate the pistons 50 and 51 when the 105 same are adjusted in the position as set forth in Fig. 2, whereby the pressure within the cylinder 9 to the rear of the piston 10 is free to pass through the passage-ways 54 and 55 and to the atmosphere through the 110 tubular extension 14. It is also to be observed that the point of communication of the passage-way 54 with the supplemental cylinder 52 is such that substantially instantaneously upon the outward movement of the pistons 50 and 51, the piston 51 will 115 serve to close such passage-way 54. It is also to be observed that in order to reduce the pressure within the supplemental cylinder 52 rearwardly of the piston 50, when the 120 same has been moved into said position, we provide the port 56, particularly shown in Fig. 4, which is also under control of the piston 50. In order to prevent increased pressure created within the cylinder 1 in 125 advance of the piston 7 from entering with- 130

in the supplemental cylinder 52 through the port 56, we employ the check valve 57 of conventional type.

In order that the pressure within the supplemental cylinder 52 rearwardly of the piston 50 may be equalized with the pressure within the brake cylinder 1 when the pressure from the train line is increased, we find it of advantage to employ the conduit or port 58 leading from a point rearwardly of the piston 50 and terminating in such proximity to the open end of the supplemental cylinder 52 as to be in communication with the brake cylinder 1 after the pistons 50 and 51 have been forced inwardly to the position shown in Fig. 2 and in order to retain such pressure within the supplemental cylinder 52, rearwardly of the piston 50, we interpose within such port 58 the check valve 59 which may also be of any conventional form. If it should occur that the compression created by the inward movement of the piston 50 should be in excess of pressure within the brake cylinder 1, we find it of advantage to provide in the valve portion 48, of the stem or rod 49, the port 60 adapted to communicate with the passage-way 42, hereinbefore referred to, whereby it will be readily perceived that such excessive compression will be equalized through the communication with the atmosphere, but it is also to be noted that the extent of the port 60 is such as to be entirely cut off at the time the valve 48 is in its closed position.

From the foregoing description, it is thought to be obvious that a fluid operated brake constructed in accordance with our invention is of an extremely simple and comparatively inexpensive nature and is particularly well adapted for use by reason of the convenience and facility with which it may be applied and by reason of the substantially automatic manner in which it operates and it will also be obvious that our invention is susceptible of some change and modification without material departure from the principles and spirit thereof and for this reason we do not wish to be understood as limiting ourselves to the precise arrangement and formation of the several parts herein shown in carrying out our invention in practice.

What is claimed is:—

- 55 1. In a fluid pressure brake, a brake cylinder, a brake piston within the cylinder, an auxiliary reservoir in communication with the brake cylinder at two points, one of such points being rearwardly of the piston, a connection between the brake cylinder and the train line, and regulatable means for controlling the flow through the second connection between the auxiliary reservoir and the brake cylinder.
- 60 2. In a fluid pressure brake, a brake cyl-

inder, an auxiliary reservoir in communication with the brake cylinder at an end and side thereof, connections between the opposite end of the brake cylinder and the train line, a brake piston within the cylinder, and regulatable means for controlling the flow through the connections between the auxiliary reservoir and the brake cylinder through the side thereof.

3. In a fluid pressure brake, a brake cylinder, an auxiliary reservoir in communication with the brake cylinder at an end and side thereof, connection between the opposite end of the brake cylinder and the train line, a brake piston within the cylinder, and means for automatically stopping the flow through the connection between the auxiliary reservoir and the brake cylinder through a side thereof when the pressure within the auxiliary reservoir has reached a predetermined degree.

4. In a fluid pressure brake, a brake cylinder, an auxiliary reservoir in communication therewith, a brake piston within the cylinder, an auxiliary cylinder carried by the brake piston, such auxiliary cylinder being provided with a tubular extension leading exteriorly of the brake cylinder, a piston within the auxiliary cylinder, a brake rod operatively connected with the piston of the auxiliary cylinder and directed through the tubular extension thereof, such brake rod being of less transverse diameter than the bore of the diameter of the tubular extension, and means whereby the pressure at the rear of the piston of the auxiliary cylinder may be discharged through the tubular extension of the auxiliary cylinder when the brake is released.

5. In a fluid brake, a brake cylinder, an auxiliary reservoir in communication with the brake cylinder, a main piston within the brake cylinder, an auxiliary cylinder carried by the brake piston, a piston mounted within the auxiliary cylinder, a brake rod connected to the piston within the auxiliary cylinder, and means operable by the pressure within the brake cylinder in advance of the main piston for controlling the flow from the auxiliary reservoir to the rear of the piston in the auxiliary cylinder.

6. In a fluid pressure brake, a brake cylinder, a brake piston within the cylinder, an auxiliary reservoir in communication with the brake cylinder at two points, one of such points being rearwardly of the piston, a connection between the brake cylinder and the train line, and means for automatically stopping the flow through the second connection between the auxiliary reservoir and the brake cylinder when the pressure within the auxiliary reservoir has reached a predetermined degree.

7. In a fluid pressure brake, a brake cylinder, an auxiliary reservoir in communica-

tion therewith, and a valve for controlling the flow from the train line to the brake cylinder, such valve including a cylinder interposed in the cross-over and having a passage-way in communication with the cylinder and with the atmosphere, such cylinder being also provided with a branch passage-way in communication with the first mentioned passage-way and with that portion 10 of the cross-over between the cylinder and the brake cylinder, a check valve interposed in the passage-way between the communication thereof with the cylinder and the branch passage-way, a piston mounted for 15 reciprocating movement within the valve cylinder and adapted to control the flow of the fluid through the passage-way, and a stem carried by such piston intersecting the passage-way, such stem being provided 20 with an opening to register with the passage-way when the piston is moved in one direction.

8. In a fluid pressure brake, a brake cylinder, an auxiliary reservoir in communication therewith, and a valve for controlling the flow from the train line to the brake cylinder, such valve including a cylinder interposed in the cross-over and having a passage-way in communication with the cylinder and with the atmosphere, such cylinder being also provided with a branch passage-way in communication with the first mentioned passage-way and with that portion 30 of the cross-over between the cylinder and the brake cylinder, a check valve interposed in the passage-way between the communication thereof with the cylinder and the branch passage-way, a piston mounted for 35 reciprocating movement within the valve cylinder and with the atmosphere, such cylinder being also provided with a branch passage-way in communication with the first mentioned passage-way and with that portion 40 of the cross-over between the cylinder and the brake cylinder, a check valve interposed in the passage-way between the communication thereof with the cylinder and the branch passage-way, a piston mounted for 45 reciprocating movement within the valve cylinder and adapted to control the flow of the fluid through the passage-way, and a stem carried by such piston intersecting the passage-way, such stem being provided with an opening to register with the passage-way 50 when the piston is moved in one direction, said stem being provided with a port in communication with the opening in the stem and with the interior of the cylinder when the piston is in such position as to have the opening of the stem in register with the passage-way.

9. In a fluid pressure brake, a brake cylinder, an auxiliary reservoir in communication therewith, and a valve for controlling the flow from the train line to the brake cylinder, such valve including a cylinder interposed in the cross-over and having a passage-way in communication with the cylinder and with the atmosphere, such cylinder being also provided with a branch passage-way in communication with the first mentioned passage-way and with that portion 60 of the cross-over between the cylinder and the brake cylinder, a check valve inter-

posed in the passage-way between the communication thereof with the cylinder and the branch passage-way, a piston mounted for reciprocating movement within the valve cylinder and adapted to control the flow of the fluid through the passage-way, and a stem carried by such piston intersecting the passage-way, such stem being provided with an opening to register with the passage-way when the piston is moved in one direction, such stem being provided with a channel to afford communication between the brake cylinder through the passage-way and the valve cylinder when the piston is moved in a direction to open the communication between the passage-way and the brake cylinder and to close the communication of such passage-way with the atmosphere. 65 70 75 80

10. In a fluid pressure brake, a brake cylinder, a brake piston within the cylinder, an auxiliary reservoir in communication with the brake cylinder at two points, one of such points being rearwardly of the brake piston, and means for automatically stopping the flow through the connection between the auxiliary reservoir and the second connection with the brake cylinder comprising a casing interposed in such second connection, means for controlling the flow through the bore of such casing in one direction, a basket carried by the casing and provided with a passage-way in communication with the bore of the casing at a point between the controlling means of the bore and the auxiliary reservoir and with the interior of the basket, a second valve for controlling the flow 100 through the bore of the casing, and fluid operated means within the basket connected with such second valve for moving such second valve to closed position when the pressure within the auxiliary reservoir has 105 reached a predetermined degree. 90 95 100 105

11. In a fluid pressure brake, a brake cylinder, a brake piston within the cylinder, an auxiliary reservoir in communication with the brake cylinder at two points, one of such points being rearwardly of the brake piston, and means for automatically stopping the flow through the connection between the auxiliary reservoir and the second connection with the brake cylinder comprising a casing interposed in such second connection, means for controlling the flow through the bore of such casing in one direction, a basket carried by the casing and provided with a passage-way in communication with the bore of the casing at a point between the controlling means of the bore and the auxiliary reservoir and with the interior of the basket, a second valve for controlling the flow through the bore of the casing, and regulatable fluid operated means within the basket connected with such second valve for moving such second valve to 110 115 120 125

closed position when the pressure within the auxiliary reservoir has reached a predetermined degree.

12. In a fluid pressure brake, a brake cylinder, an auxiliary reservoir in communication with the brake cylinder, a main piston within the brake cylinder having a channel in the periphery thereof, the rear portion of the brake cylinder being provided with 5 elongated grooves adapted to be open to the channel of the main piston when such main piston is substantially in release position, an auxiliary cylinder carried by the brake piston, a piston mounted within the 10 auxiliary cylinder, a brake rod connected to the piston within the auxiliary cylinder, such main piston being provided with a substantially radially directed passage-way in communication with the peripheral groove 15 of the main piston and with the interior of the auxiliary cylinder rearwardly of the piston therein, the channels in the walls of the brake cylinder being in communication with the auxiliary reservoir upon initial 20 movement of the main piston, and means operable by the pressure within the brake cylinder in advance of the main piston for controlling the flow through the radially disposed 25 passage-way of the main piston.
13. In a fluid pressure brake, a brake cylinder, an auxiliary reservoir in communication with the brake cylinder, a main piston within the brake cylinder having a channel in the periphery thereof, the rear portion 30 of the brake cylinder being provided with elongated grooves adapted to be open to the channel of the main piston when such main piston is substantially in release position, an auxiliary cylinder carried by the brake piston, a piston mounted within the auxiliary cylinder, a brake rod connected to the piston within the auxiliary cylinder, such main piston being provided with a substantially 35 radially directed passage-way in communication with the peripheral groove of the main piston and with the interior of the auxiliary cylinder rearwardly of the piston therein, the channels in the walls of the brake cylinder being in communication with the auxiliary reservoir upon initial 40 movement of the main piston, means operable by the pressure within the brake cylinder in advance of the main piston for controlling the flow through the radially disposed 45 passage-way of the main piston, and a check valve for controlling the flow through the radially disposed passage-way in the main piston.
14. In a fluid pressure brake, a brake cylinder, an auxiliary reservoir in communication with the brake cylinder, a main piston within the brake cylinder having a channel in the periphery thereof, the rear portion of the brake cylinder being provided 50 with elongated grooves adapted to be open

to the channel of the main piston when such main piston is substantially in released position, an auxiliary cylinder carried by the brake piston, a piston mounted within the auxiliary cylinder, a brake rod connected to the piston within the auxiliary cylinder, such main piston being provided with a substantially radially directed passage-way in communication with the peripheral groove of the main piston and with the interior of the auxiliary cylinder rearwardly of the piston therein, the channels in the walls of the brake cylinder being in communication with the auxiliary reservoir upon initial movement of the main piston, a supplemental cylinder having its forward face open carried by the auxiliary cylinder, a piston mounted for reciprocating movement within such supplemental cylinder, and a stem carried by such piston intersecting the radially disposed passage-way of the main piston whereby movement of the piston within the supplemental cylinder serves to control the flow through the radially disposed passage-way of the main piston. 90

15. In a fluid pressure brake, a brake cylinder, an auxiliary reservoir in communication with the brake cylinder, a main piston within the brake cylinder having a channel in the periphery thereof, the rear portion of the brake cylinder being provided with elongated grooves adapted to be open to the channel of the main piston when such main piston is substantially in released position, an auxiliary cylinder carried by the brake piston, a piston mounted within the auxiliary cylinder, a brake rod connected to the piston within the auxiliary cylinder, such main piston being provided with a substantially radially directed passage-way in communication with the peripheral groove of the main piston and with the interior of the auxiliary cylinder rearwardly of the piston therein, the channels in the walls of the brake cylinder being in communication with the auxiliary reservoir upon initial movement of the main piston, a supplemental cylinder carried by the auxiliary cylinder, spaced pistons mounted for reciprocal movement within the supplemental cylinder, a valve stem operatively connected with such pistons and adapted to intersect the radially disposed passage-way of the main piston whereby the reciprocating movements of the pistons control the flow through such passage-way, such supplemental cylinder and auxiliary cylinder being provided with a passage-way in communication with the supplemental cylinder and the auxiliary cylinder adjacent the forward end thereof, and a second passage-way in communication with the supplemental cylinder and the auxiliary cylinder rearwardly of the piston within such auxiliary cylinder, the points of communication of such passage-ways with 100 105 110 115 120 125 130

the supplemental cylinder being between the pistons within such supplemental cylinder when such pistons are at the limit of their inward movement.

- 5 16. In a fluid pressure brake, a brake cylinder, an auxiliary reservoir in communication with the brake cylinder, a main piston within the brake cylinder having a channel in the periphery thereof, the rear portion of the brake cylinder being provided with elongated grooves adapted to be open to the channel of the main piston when such main piston is substantially in released position, an auxiliary cylinder carried by the 10 brake piston, a piston mounted within the auxiliary cylinder, a brake rod connected to the piston within the auxiliary cylinder, such main piston being provided with a substantially radially directed passage-way 15 in communication with the peripheral groove of the main piston and with the interior of the auxiliary cylinder rearwardly of the piston therein, the channels in the walls of the brake cylinder being in communication with the auxiliary reservoir upon initial movement of the main piston, a supplemental cylinder carried by the auxiliary cylinder, spaced pistons mounted for reciprocating movement within the supplemental cylinder, a valve stem operatively connected with such pistons and adapted to intersect the radially disposed passage-way of the main piston whereby the reciprocating movements of the pistons control the flow through such passage-way, such supplemental cylinder and auxiliary cylinder being provided with a passage-way in communication with the supplemental cylinder and the auxiliary cylinder adjacent the forward end thereof, and a second passage-way in communication with the supplemental cylinder and the auxiliary cylinder rearwardly of the piston within such auxiliary cylinder, the points of communication of such passage-ways with the supplemental cylinder being between the pistons within such supplemental cylinder when such pistons are at the limit of their inward movement, the innermost piston within the supplemental cylinder being adapted to close the last mentioned passage-way between the supplemental cylinder and the auxiliary cylinder upon outward movement of the pistons within the supplemental cylinder, such supplemental cylinder being provided with a check-controlled port under control of the innermost piston within the supplemental cylinder. 20 25 30 35 40 45 50 55 60 65
17. In a fluid pressure brake, a brake cylinder, an auxiliary reservoir in communication with the brake cylinder, a main piston within the brake cylinder having a channel in the periphery thereof, the rear portion of the brake cylinder being provided with elongated grooves adapted to be open to the channel of the main piston when such main piston is substantially in release position, an auxiliary cylinder carried by the brake piston, a piston mounted within the auxiliary cylinder, a brake rod connected to the piston within the auxiliary cylinder, such main piston being provided with a substantially radially directed passage-way in communication with the peripheral groove of the main piston and with the interior of the auxiliary cylinder rearwardly of the piston therein, the channels in the walls of the brake cylinder being in communication with the auxiliary reservoir upon initial movement of the main piston, a supplemental cylinder having its forward face open car-

10 15 20 25 30 35 40 45 50 55 60 65 70 75 80 85 90 95 100 105 110 115 120 125 130

ary cylinder, a brake rod connected to the piston within the auxiliary cylinder, such main piston being provided with a substantially radially directed passage-way in communication with the peripheral groove of the main piston and with the interior of the auxiliary cylinder rearwardly of the piston therein, the channels in the walls of the brake cylinder being in communication with the auxiliary reservoir upon initial movement of the main piston, a supplemental cylinder carried by the auxiliary cylinder, spaced pistons mounted for reciprocating movement within the supplemental cylinder, a valve stem operatively connected with such pistons and adapted to intersect the radially disposed passage-way of the main piston whereby the reciprocating movements of the pistons control the flow through such passage-way, such supplemental cylinder and auxiliary cylinder being provided with a passage-way in communication with the supplemental cylinder and the auxiliary cylinder adjacent the forward end thereof, and a second passage-way in communication with the supplemental cylinder and the auxiliary cylinder rearwardly of the piston within such auxiliary cylinder, the points of communication of such passage-ways with the supplemental cylinder being between the pistons within such supplemental cylinder when such pistons are at the limit of their inward movement, the innermost piston within the supplemental cylinder being adapted to close the last mentioned passage-way between the supplemental cylinder and the auxiliary cylinder upon outward movement of the pistons within the supplemental cylinder, such supplemental cylinder being provided with a check-controlled port under control of the innermost piston within the supplemental cylinder.

18. In a fluid pressure brake, a brake cylinder, an auxiliary reservoir in communication with the brake cylinder, a main piston within the brake cylinder having a channel in the periphery thereof, the rear portion of the brake cylinder being provided with elongated grooves adapted to be open to the channel of the main piston when such main piston is substantially in release position, an auxiliary cylinder carried by the brake piston, a piston mounted within the auxiliary cylinder, a brake rod connected to the piston within the auxiliary cylinder, such main piston being provided with a substantially radially directed passage-way in communication with the peripheral groove of the main piston and with the interior of the auxiliary cylinder rearwardly of the piston therein, the channels in the walls of the brake cylinder being in communication with the auxiliary reservoir upon initial movement of the main piston, a supplemental cylinder having its forward face open car-

ried by the auxiliary cylinder, a piston mounted for reciprocal movement within such supplemental cylinder, and a stem carried by such piston intersecting the radially disposed passage-way of the main piston whereby movement of the piston within the supplemental cylinder serves to control the flow through the radially disposed passage-way of the main piston, the inner extremity 10 of such stem being provided with a port in communication with the radially disposed passage-way of the main piston and adapted to communicate with the interior of the supplemental cylinder after initial outward 15 movement of the piston within the supplemental cylinder.

19. In a fluid pressure brake, a brake cylinder, a brake piston within the cylinder, an auxiliary reservoir in communication 20 with the brake cylinder at a plurality of points, a connection between the brake cylinder and the train line, and regulatable

means for controlling the flow through one of the connections between the auxiliary reservoir and the brake cylinder.

25

20. In a fluid pressure brake, a brake cylinder, a brake piston within the cylinder, an auxiliary reservoir in communication with the brake cylinder at a plurality of points, a connection between the brake cylinder and the train line, and means for automatically stopping the flow through one of the connections between the auxiliary reservoir and the brake cylinder when the pressure within the auxiliary reservoir has 30 reached a predetermined degree.
